UNITED STATES PATENT OFFICE.

HARRY LANDSIEDEL, OF CINCINNATI, OHIO, ASSIGNOR TO THE DALTON ADDING MACHINE COMPANY, OF CINCINNATI, OHIO, A CORPORATION OF OHIO.

ADDING-MACHINE.

1,278,687.

Specification of Letters Patent. Patented Sept. 10, 1918.

Application filed February 28, 1916. Serial No. 80,939.

To all whom it may concern:

Be it known that I, HARRY LANDSIEDEL, a citizen of the United States, residing at the city of Cincinnati, county of Hamilton, and 5 State of Ohio, have invented a new and useful Adding-Machine, of which the following is a specification.

This invention relates to adding machines.

Many of the features of the present invention have specific reference to adding machines of that type in which there is a movable carriage having pins mounted therein which are settable to represent the numbers to be added, and in reference to 10 these features the object of the invention is to provide novel mechanism to increase the accuracy and efficiency of the machine by devices under control of the number-setting mechanism for locking the clearing mechanism so that, after the number-setting mechanism has started to operate, the clearing mechanism will be prevented from 15 operation, in combination with an actuating member under control of the adding mechanism for restoring said devices to position to enable the clearing mechanism to operate. In connection with the mechanism for the attainment of this object provision is made for requiring an additional operation of the 20 main shaft of the machine after the last number or item has been listed, in order to complete the act of transferring or carrying from lower to higher order before the clearing mechanism may be operated.

Other features of the invention have reference to the clearing mechanism and in respect of these features, the object of the present invention is to provide devices under control of the adding and clearing mechanisms and including a part of the printing mechanism for printing a sign or symbol to indicate a clear condition of the adding mechanism.

A further object of the invention is to provide a machine including adding and clearing and printing mechanisms and in which the printing mechanism is operable to print the lists of the numbers which are then automatically added by the adding mechanism, 45 in combination with clearing mechanism for coöoperating with the adding mechanism,

and means controlled by the adding mechanism for positioning a part of the printing mechanism for operation so that when the controlling devices of the printing mechanism are operated after the adding mechanism has been cleared and while the clearing mechanism is in position for coöperation with the adding mechanism, one part of the mechanism which operates in the printing 50 of items and the totals thereof will be operated to print a character indicating a clear condition of the adding mechanism, to the end that the user of the machine may be affirmatively informed of the clear condition 55 of the adding mechanism. In the specific form of the invention illustrated in the drawings, I utilize one of the type-driving hammers which is used in the printing of 60 numbers and the totals thereof, as the type- 65 driving hammer which is operated to print the character indicating a clear condition of the adding mechanism. In this particular, the invention is further differentiated from machines heretofore used by the novel combination of elements constituting the train 70 of printing mechanism so that in so far as I am aware the form of printing mechanism, controlled in this manner for the purposes mentioned, is itself entirely novel.

Another object of the invention has reference to the devices optionally operable by the operator subsequent to the setting up of a number preliminary to adding the same, whereby the operator may restore the set up 75 parts to their idle positions, thus erasing or eliminating from the machine any number after it has been set up and prior to addition thereof. These optionally operable devices, however, do not release the clearing mechanism but they are arranged in such relation to the locking devices, which are under control of the number-setting mechanism, that such locking devices are left in position to prevent operation of the clearing mechanism; so that an operation of the main shaft of the machine, to move the adding mechanism to and from operative engagement with the recording mechanism, is necessary to release the locking devices from 80 the clearing mechanism.

With the foregoing and other objects in

view, all of which will appear as the description proceeds, I have embodied my invention in a preferred form which I have illustrated in the accompanying drawings, in 5 which—

Fig. 1 is a side elevation of the adding and listing and clearing mechanisms in their normal positions.

Fig. 2 is a side elevation of the clearing 10 mechanism set for operation and illustrating the connections controlled thereby for coöperating with the locking devices to prevent the setting of numbers.

Fig. 3 is a detailed view illustrating the 15 locking devices which have been positioned by operation of the number-setting mechanism to prevent operation of the clearing mechanism.

Fig. 4 is a detailed view of the same parts 20 showing their position after the number-setting devices have returned to idle position, leaving the locking devices in engagement with the clearing mechanism so as to require an additional operation of the controlling elements of the machine to complete 25 the act of transferring or carrying in the process of addition before the clearing mechanism may operate.

Fig. 5 is a view of the optionally operable 30 connections for restoring to idle position the number-setting mechanism in order to erase or eliminate from the machine any number which has been set up therein, before such number has been listed or introduced into 35 the adding mechanism.

Fig. 6 is a plan view of the same mechanism.

Fig. 7 is a perspective view of the locking 40 devices which coöperate with the number-setting and clearing mechanisms.

Figs. 8, 9 and 10 are detailed views of different parts of the locking devices.

Fig. 11 is a perspective view of the connections on the main shaft for restoring the 45 movable carriage to its idle position as an incident to the return of the main shaft after each operation.

Fig. 12 is a detailed view of the spring connections illustrated in Fig. 11.

Fig. 13 is a perspective view of the clearing 50 devices.

Fig. 14 is a detailed view of a link and its actuating lever which serves to position the adding mechanism for adding and clearing 55 operations.

Figs. 15 and 16 are detailed views of the devices which operate the link to position the adding mechanism for adding operations.

Fig. 17 is a view illustrating the mechanism 60 under control of the adding mechanism for printing a character to indicate a clear condition of said mechanism; in this view the adding mechanism is in its normal position in connection with the operating racks,

and when retained in this position by the clearing mechanism the train of connections therefrom will cause the printing mechanism to print a character as an incident to the operation of the main shaft.

Fig. 18 is a view of the same parts illustrating the manner in which the connections under control of the adding mechanism, for printing a character to indicate a clear condition of the machine, are disabled or rendered inoperative as an incident to the rocking of the main shaft when the clearing mechanism is not in position for clearing the adding mechanism.

The numbers to be added and listed are 80 introduced into the machine by operation of the numeral keys 1 which are operative to set pins 2 to represent numbers to be added and listed. The pins 2 are mounted in a transversely movable carriage 3 supported by rails 4 upon which said carriage is laterally movable. The carriage is moved step-by-step laterally in one direction as an incident to the operation of the numeral keys so as to place the rows of pins 2 successively over the ends of the numeral key levers. This step-by-step movement may be controlled by any appropriate escapement mechanism which, however, is not illustrated in the drawings, because the escapement mechanism *per se* constitutes no part of the present invention, it being sufficient for present purposes to understand that the carriage is movable laterally in the usual manner, as required to place the rows of pins 85 successively in position over the ends of the key levers. 90

A link 5 has one end pivoted to the carriage and the opposite end pivoted to an upright rock shaft 7, so that by turning the shaft 7 in one direction the carriage will be moved as required to place the rows of pins successively over the key levers and by turning the shaft 7 in the other direction the carriage will be restored to its starting 105 point. A spring 8 has one end connected to an arm 9 attached to the rock shaft and the other end connected to an appropriate member and is effective to actuate the shaft 7 in the direction required to move the carriage 110 to place the rows of pins successively adjacent to the key levers.

The pins 2 constitute differential stops for limiting movement of the type-carriers 10 and the racks 11 which are the actuators of the adding mechanism. The type-carriers and racks are pivotally supported by a rock shaft 12 and are actuated in a forward direction by springs 13 connecting extensions on the type-carriers with a stationary part 14. The type-carriers and racks are restored to their starting points after each operation by a rod 15 supported by two arms 16, the upper end of which are attached to the rock shaft 12. One of the arms 16 is 115 120 125 130

connected with the main shaft 17 of the machine by a link 18 and these parts are normally retained in position to hold the racks and type-carriers in their idle adjustments 5 by spring 19 suitably connected with the rock shaft. When it is desired to actuate the type-carriers to record the numbers represented by the differential stops 2 the main shaft 17 is actuated in a forward direction 10 by a handle 20, or otherwise, as desired, to cause the arms 16 to carry the rod 15 away from the type-carriers and racks and permit the springs 13 to operate them.

The type-carriers have type 21 at their 15 forward ends which, by the operation described, are selectively adjustable in printing position adjacent to the platen 22. After the type-carriers have become stationary the type thereon, which are alined at 20 the printing line, are driven to print by the operation of hammers 23 and, after the printing has been effected, the type-carriers are restored to their starting points by retraction of the main spring 19, returning the 25 shaft 17 and its connections to their starting points.

The hammers 23 and the type-carriers are equal in number. The hammers are pivotally supported upon a rod 24 extending 30 transversely in front of the type-carriers. Each of the hammers is connected with a corresponding coupling 25 by a projection 26 on the lower end of the hammer extending into a notch 27 in the coupling, so that 35 when the couplings are operated by their actuators, the hammers will also be operated. The forward end of each coupling is carried by a comb-plate 28 and the rear or inner end of each coupling rests upon a corner 40 responding positioning lever 29. In normal position the rear or inner ends of the couplings and the forward ends of the levers 29 are held depressed by springs 30 connected to the couplings and exerting their 45 power to draw them inwardly and downwardly. The couplings and levers 29 are retained in proper relative position by a comb-plate 31. The levers 29 are supported by a shaft 32 and the rear ends of said levers 50 are adjacent to the lower surfaces of the type-carriers, so that when any type-carrier moves forward beyond the position required to place the zero type at the printing line a shoulder 33 on the type-carrier so 55 moving will engage the rear or inner end of the lever 29 and thereby raise the forward end of said lever from the position illustrated in Fig. 18 to the position illustrated in Fig. 17.

60 For each coupling and its corresponding hammer there is an actuator 34. Said actuators are pivotally supported by a rock shaft 35 and are provided with extensions 36 which are of such length that they may 65 move over the rear ends of the couplings 25

without engaging therewith when said couplings are in their lower positions, but when the couplings are raised by contact of the shoulders 33 with the rear ends of the levers 29 as described, or otherwise, the ends of 70 said couplings are in the path of movement of the extensions 36 on the actuators. Each of the actuators is connected with a rod 37 by a spring 38, the rod 37 being supported between two arms 39 attached to the 75 rock shaft 35.

The main shaft 17 of the machine has an arm 40 which is connected by a link 41 with a lever 42 pivoted on the rock shaft 35. On forward movement of the main shaft 17 the 80 lower end of the lever 42 is moved in a forward direction and, by engaging a pin 43 on an arm 44 which is attached to the rock shaft 35, such movement of the lever 42 actuates the shaft 35 to raise the forward ends 85 of the arms 39 as required to extend or tension the springs 38. During this operation movement of the hammers and their couplings and the actuators 34 is prevented.

The device for preventing movement of 90 the hammers and their couplings and the actuators includes a revoluble member 45 which is arcuate in cross section and which extends transversely in front of the hammers and constitutes an abutment for the 95 projection 46 at the lower ends of the hammers. In its forward position the arm 44 becomes latched with a member 47 so that, when the shaft 17 starts on its return movement, the lever 42 will be moved rearwardly 100 relative to the arm 44. A pin 48 on the lower end of the lever 42 engages with a lever 49 pivoted on the arm 44 and causes the upper end of said lever 49 to engage a projection 50 on an arm 51 attached to the 105 end of the member 45, thereby turning said member 45 to position to permit the hammers to operate, at which time the actuators 34 are operated by their springs 38 to force the couplings 25 forwardly to drive the 110 hammers against the type. As the lower end of the lever 42 approaches nearly to its starting point, a cam 52 on the lower end of said lever rubs against and disengages the member 47 from the shoulder on the arm 44 with 115 which it was engaged. The spring 53 connecting the lever 49 with the pin 48 had been expanded when the arm 44 had been moved forwardly and, when the member 47 is released from the arm 44 by the cam 52, the 120 spring 53 retracts and moves the arm 44 rearwardly to its normal position thereby turning the shaft 35 in a direction to lower the arm 39 attached thereto and cause the rod 54 carried by said arms to depress the 125 actuators 34. The member 45 is restored to idle position after being released from the lever 49 by a spring 55 connecting the arm 51 with the abutment pin 56, and the return movement of the member 45 also retracts 130

the hammers from the type by rubbing against the oblique surfaces on the lower edges of the projections 46.

The foregoing general description of the printing or listing mechanism, which is a part of the combination comprising my invention, is deemed sufficient for a complete understanding of the additional subject-matter which I will now describe.

- 10 The adding wheels 57, which are of usual construction, are independently revoluble upon a shaft 58 supported by a swinging frame 59 by operation of which the adding wheels are engaged with and disengaged 15 from the actuating racks 11. The shaft 58 is retained in proper position by links 60 whose rear ends are connected to the shaft 58 and whose front ends are connected to a rod 61.
- 20 The device for swinging the frame 59 includes a link 62 (Figs. 1, 2, 13 and 14), having its rear end pivoted to one of the members of the frame 59 and its forward end adjacent to a lever 63 on a rock shaft 64.
- 25 A pin 65 on the link 62 rests upon a lever 66 attached to a rock shaft 67, said pin 65 being connected with the lever 66 by a spring 68. The lever 66 is held yieldingly in a raised position by a spring 69 connecting an 30 arm of said lever with another part of the machine. When the link 62 is supported in its raised position by the lever 66 a notch 70 (Figs. 13 and 14), in said link receives a pin 71 on the lever 63, as a result of which connection turning of the shaft 64 in one direction will actuate the link 62 to move the frame 59 as required to lower the shaft 58 to disengage the adding wheels 57 from the 35 actuating racks.
- 40 The shaft 64 has a bifurcated lever 72 attached thereto, and said shaft also supports a pivoted member 73 having a pin 74 extending between the arms of the lever 72. A spring 75, connected to the upper end of the 45 member 73, serves to hold said member normally in its idle position and to coöperate with said member to enable it to perform its functions of rocking the shaft 64.

A segmental arm 76 attached to the shaft 50 17 engages the lower end of the member 73 on forward turning of the shaft 17 and thereby turns the shaft 64 in the direction required to cause the lever 63 thereon to actuate the link 62 in order to operate the 55 frame 59 in the direction which will disengage the wheels 57 from their actuating racks. The forward turning of the shaft 17 moves the segmental arm 76 beyond the member 73, at which time the spring 75 retracts to move the member 73 the distance permitted by the pin 74 between the arms of the lever 72, so that when the shaft 17 makes its return movement the segmental arm 76 will engage the member 73 and turn 60 the shaft 64, in the direction opposite from

that in which it was first turned, a distance sufficient to cause the connections from said shaft 64 to move the adding wheels into mesh with the racks before the rod 15 starts the racks on their return movement.

70 From the foregoing it will be clear that the adding wheels are disengaged from the racks as an incident to the turning of the shaft 17 in a forward direction and that the disengagement is effected prior to any forward movement of the racks. The adding wheels are reengaged with the racks as an incident to the backward turning of the shaft 17 prior to any return movement of the racks so that the entire return movement 80 of the racks will be utilized to actuate the adding wheels.

85 For clearing operations it is necessary to retain the adding wheels in mesh with the racks during the forward movement of the latter and this is effected by the mechanism which I will now describe.

90 The key lever 77 has a depending arm which is pivoted upon a support 78 and has an upwardly extending arm provided with a slot 79 which receives a pin 80 extending from an arm 81 attached to the rock shaft 67. By depressing the forward end of the lever 77 the shaft 67 will be turned in opposition to the spring 69, thus moving downwardly the rear end of the lever 66 and causing the spring 68 to move the forward end of the link 62 downwardly with the lever 66. This disconnects the link 62 from the pin 71 on the upper end of the lever 63 and leaves the lever 63 free to operate without actuating the link 62 so that the adding wheels will remain in engagement with the racks during their forward movement, thus clearing the 100 adding mechanism. When the lever 63 completes the extent of its movement by the turning of the shaft 64 as a result of the forward movement of the segmental plate 76, a pin 82 on the lower end of the lever 63 becomes seated in a notch 83 in the lower edge 110 of the link 62, so that when the segmental arm 76 starts on its return movement the lever 63 will actuate the link 62 rearwardly thus moving the frame 59 as required to disengage the adding wheels from the actuating 115 racks and leaving the adding wheels clear. This clearing action will be effected by holding the key lever 77 depressed during the return movement of the racks, but if it is desired to retain the total in the adding wheels 120 after the total has been printed by the operation above described, this may be done by retaining the adding wheels in engagement with the racks during the return movement of the latter, thus resetting the adding 125 wheels in position to represent the total which had been printed. The adding wheels will be retained in mesh with the racks by releasing the key lever 77 and permitting the spring 69 to retract to actuate the parts 130

controlled thereby to disengage the link 62 from the pin 82, thus leaving the shaft 64 free to turn on its return movement without actuating the link 62.

5 A releasable latch is provided for the clearing mechanism which will be released automatically to enable the parts to return to their normal positions so that the adding wheels will be retained in mesh with the 10 racks. The latch mentioned includes a pivoted member 84 (Figs. 1 and 2) having a hook portion on its upper end to engage a projection 85 on a depending portion of the lever 66, as illustrated in Fig. 2. The member 15 84 is actuated by the spring 69 to maintain its connection with the projection 85 so that when the key lever 77 is depressed to the position illustrated in Fig. 2 it will be retained in its depressed position until the 20 racks complete their forward movement, at which time the member 84 will be released from the projection 85 by a pin 86 extending from the arm 87 attached to the shaft 17, said pin operating against an adjacent extension of the member 84. Thus the total 25 represented in the wheels 57 and printed in the manner described will be automatically retained in the adding wheels. However, if it is desired to clear the adding mechanism 30 this may be done by holding the key lever 77 in its depressed position until after the pin 86 moves away from the extension of the member 84, thus leaving the member 84 in latched engagement with the projection 85. 35 The usual detaining plate 88 is pivoted upon the carriage 3 and engages the usual depending portions 89 of the racks to prevent movement of the racks, except those corresponding to the digits represented in 40 the carriage. However, when it is desired to operate the racks in clearing operations it is necessary to release the detaining plate 88 and this is effected by a device under control of the key lever 77. The lever 66 has an upward extension to which a link 90 is pivoted and the rear end of said link operates in a slot within a support 91. A depending arm 92 on the link is over the plate 88 so that rearward movement of the link 90 causes 45 said arm 92 to depress the plate 88 to disengage the same from the extensions 89 of the racks. Thus the racks are released and are enabled to operate in clearing operations. 50

Referring next to the devices under control of the number-setting mechanism for locking the clearing mechanism to prevent operation thereof after operation of any part of the number-setting mechanism and prior to the completion of the transferring 55 or carrying operations, attention is directed to the fact that the locking action of the locking devices is effected by the number-setting mechanism, and that the initial portion of the unlocking action is effected by 60 the return movement of the number-setting 65

devices, and is subsequently completed by parts under control of the adding mechanism by a subsequent operation, so that the complete adding functions of the adding mechanism must be completed before the locking devices will be released from the clearing mechanism. 70

A locking member is pivoted upon a support 93 and comprises a horizontal arm 94 and an upper arm 95. The arm 94 extends 75 under a projection 96 depending from the link 90 and is in such position that when carrying or transferring is completed and when no part of the number-setting mechanism has been operated after completion of 80 the carrying or transferring operation, the projection 96 may move freely over the arm 94. However, when the number-setting mechanism is operated the arm 94 is engaged with the projection 96 to prevent operation 85 thereof until the number-setting mechanism is returned to idle position and the act of transferring or carrying has been completed. The means for enabling the arm 94 to engage the projection 96 includes a cam plate 90 97 attached to the upper end of the rock shaft 7 which actuates the differential mechanism, said cam plate being arranged to cooperate with a depending arm 98 constituting a part of the lock control device. This 95 member of the lock control device is also pivoted upon the support 93 and in addition to the arm 98 includes an arm 99 having a laterally extending pin 100 connected with a pin 101 on an arm of the lock device by a 100 retractile spring 102.

When the carriage 3 is in its home or idle position the cam 97 engages the edge of the arm 98 and thereby holds the arm 99 in its lowest adjustment, placing the spring 102 105 under tension. A link 103 has its forward end pivoted to one of the members of the frame 59 and its rear end resting upon the pin 100. A pin 104 extends laterally from the link 103 and is arranged to engage 110 against the rear edge of the arm 95 to actuate the locking device, as required to hold the arm 94 thereof in position to permit operation of the link 90 by the clearing mechanism. 115

The first leftward step by the carriage 3, when any of the numeral keys 1 is operated, results in the shaft 7 moving the cam 97 (Fig. 6) out of engagement with the arm 98, whereupon the spring 102 raises the arm 120 99 and thereby raises the rear end of the link 103, which carries the pin 104 above the upper end of the arm 95, permitting partial retraction of the spring 102, which raises the arm 94 of the locking device into engagement with the projection 96, as illustrated in Fig. 3. Thus it will be seen that as an incident to the operation of any part of the number-setting mechanism, which necessarily involves a movement of the rock shaft 130

7, the locking mechanism will be set to prevent operation of the clearing mechanism. Movement of the member 98-99 is limited by a pin 105 extending into a slot in the arm 98. Locking action of the locking devices to prevent operation of the clearing mechanism is thus controlled entirely by the number-setting mechanism, while the initial portion of the unlocking action to permit operation of the clearing mechanism is effected by the return of the shaft 7 and is completed by the adding mechanism. This unlocking of the locking devices consists first in the return of the cam 97 by the shaft 7 to cause the cam to depress the arm 99 to its normal position; and second in a movement of the adding mechanism to operate the link 103 to disengage the arm 94 from the projection 96. When the locking device is placed in engagement with the projection 96, as a result of the cam 97 moving away from the arm 98, the rear extremity of the link 103, which rests upon the pin 100, raises the pin 104 above the upper end of the arm 95 (Fig. 3), thus permitting the spring 102 to engage the arm 94 with the projection 96. After the member 99 has been lowered by the return movement of the cam 97 the pin 104 remains seated upon the upper end of the arm 95, thus leaving the arm 94 in engagement with the projection 96. An additional rocking operation of the shaft 17, resulting in swinging the adding mechanism frame 59, causes the latter to move the link 103 rearwardly until the pin 104 drops behind the rear edge of the arm 95, and forward movement of the frame 59 draws forwardly with it the link 103, causing the pin 104 to engage the arm 95 and actuate it a distance sufficient to disengage the arm 94 from the projection 96. This additional operation of the shaft 17 and of the adding mechanism is the usual operation to complete the act of carrying or transferring so that the unlocking of the clearing mechanism is made dependent upon the completion of the act of carrying or transferring, and the unlocking device is, therefore, placed under control of the adding mechanism.

50 The devices under control of the clearing mechanism for preventing operation of the number-setting mechanism, include the swinging shouldered plates 106 pivoted to the comb-plate 107, (Fig. 1) which plates are pressed laterally by depression of the key lever 77 so as to position the shoulders on said plates under the numeral key levers, thus preventing depression of said levers and preventing operation of the number-setting mechanism.

55 The devices for restoring the carriage 3 to its starting point as an incident to the listing or adding of any number set up in said carriage are actuated by the shaft 17.

An arm 108 (Figs. 1, 2, 5 and 11) is pivoted on the shaft 17 at the side of the arm 87, and has a pin 109 extending over the upper end of the arm 87 between the two projections 110 which permit limited movement of the arm 108 with reference to the arm 87. A hook 111 is pivoted near the upper end of the arm 108 and is formed with an extension 112 which, when the shaft 17 is in its normal position, engages with an abutment 113. A pin 114 on the hook is engaged by the connection 115 of a spring 116, the lower end of which spring is similarly connected with a projection 117 on the arm 108, so that the tendency of the spring 116 is to raise the forward end of the hook 111. The projection 117 is connected with the base of the machine by a spring 118 so that when the shaft 17 is turned in a forward direction the spring 118 holds the arm 108 stationary until the projection 110 at the rear of the pin 109 engages said pin 109 and thereby moves the arm 108 in opposition to the spring 118. Forward movement of the arm 108 obviously permits the hook 111 to be raised by the spring 116 so that at the proper time said hook 111 engages with a pin 119 extending from a lever 120, the upper end of which is connected with a rock shaft 121. The lower end of the lever 120 is retained in a forward position by a spring 122 connecting said lever with a part of the machine frame. A link 123 connects the lower end of the lever 120 with an arm 124 pivoted to the shaft 7 and provided with a depending lug 125 which is in the same arcuate plane with a lug 126 on the arm 9. As a result of these connections when the hook 111 is engaged with the pin 119 the return movement of the shaft 17 will operate the link 123 and cause the lug 125 to engage the lug 126 and thereby turn the shaft 7 and restore the carriage 3 to its starting point. As the shaft 17 approaches its idle position the extension 112 engages the abutment 113 so that the hook 111 is eventually disengaged from the pin 119, thus permitting the spring 122 to retract and restore the lever 120 and the link 123 to their idle positions. This operation of restoring the carriage 3 to its starting point, after each number is listed or added, is automatic, but may be prevented at the option of the operator by the usual repeat connections controlled by the key 127.

The optionally operable devices for restoring the carriage 3 to its starting point without operation of the adding or listing mechanism, includes an angular lever 128 having one end attached to the rock shaft 121 and the opposite end extending vertically adjacent to the key board of the machine and provided with a finger key 129. A spring 130 connects the lever 128 with the

machine frame and restores said lever to idle position after it has been operated to actuate the carriage.

Referring next to the mechanism under control of the adding mechanism for causing the printing of a character to indicate a clear condition of the adding mechanism, it is appropriate to mention that the character is printed by a part of the usual number printing mechanism, and that I do not resort to such expedients as the provision of additional printing devices which are useless in the listing of numbers. In the particular embodiment illustrated I employ the zero type on the type-carrier in units order to print a zero character to indicate the clear condition of the adding mechanism. The positioning lever 29 in units order has a lateral projection 131 over which extends a lever 132 supported by the rod 61. It is obvious that by depression of the rear end of the lever 132 the positioning lever 29 will be operated to raise the coupling 25 in units order into the path of movement of the projecting part 36 of the actuator 34, so that the spring 38 of the actuator in units order will be extended or tensioned by the connections which are operated by the rock shaft 17, when the latter is turned in a forward direction. Furthermore, when the member 45 is turned to release the printing hammers the actuator 34 in units order will drive the corresponding hammer in a printing operation, causing said hammer to strike the zero type on the type-carrier in units order and drive the same to print.

An arm 133 extending obliquely downwardly from the rod 61, is integral with the lever 132. The lever 134 is pivoted on a support 135. The forward end of the lever 134 rests upon the upper edge of the arm 133 and the rear end of said lever 134 is adapted to be engaged by a projection 136 on one of the links 60. These parts are arranged so that when the adding mechanism is in engagement with the actuating racks 11 the projection 136 will hold the lever 134 in position to depress the rear end of the lever 132 (Fig. 17), so that the positioning lever 29 in units order supports the corresponding coupling 25 in position to operate the printing hammer. Thus it is seen that when the adding mechanism is clear a permanent indication of this fact may be given by positioning the clearing mechanism for operation and operating the controlling shaft 17.

This character to indicate a clear condition of the machine will not be printed as a result of a mere idle or useless operation of the main shaft, without positioning the clearing mechanism for operation. The printing of the character under such circumstances is prevented by raising the lever

132 to permit the forward end of the positioning lever 29 to be depressed by the weight of the parts, assisted by retraction of the spring 30. As illustrated in Fig. 18, the adding mechanism is moved out of engagement with the actuating racks 11 when the main shaft is operated without the clearing mechanism having been positioned. Thus the projection 136 releases the lever 134 and permits the lever 132 to be raised by a spring 137 connecting the arm 133 with a stationary part, which is in such position that it does not interfere with the operation of the levers in the manner described.

The arm 133 is utilized as a part of the locking device for the adding mechanism when the adding mechanism is disengaged from the racks and co-operates with a similar arm on the rod 61 to support a rod 138 which is engaged between the teeth of the adding wheels when the latter are moved out of mesh with the racks 11.

What I claim and desire to secure by Letters Patent of the United States is:—

1. In an adding machine, adding wheels, a series of racks for operating said adding wheels, and springs for operating said racks in one direction in adding and clearing operations, in combination with a plate for engaging and holding said racks, mechanism for moving said plate in one direction to selected positions to release selected numbers of said racks for adding operations, a device for moving said plate in another direction to release said racks for clearing operations, an element controlled by a part of said mechanism for preventing movement of said device in each of several positions of said plate, a spring for engaging said element with said device to prevent movement thereof, and a member for disengaging said element from said device to enable said device to be moved to release said plate from said racks.

2. In an adding machine, adding mechanism, racks for operating said adding mechanism, a plate for engaging and preventing operation of said racks, mechanism for moving said plate in one direction to selected positions to release selected numbers of said racks for adding operations, clearing mechanism for co-operating said adding mechanism and said racks in clearing operations, means actuated by a part of said clearing mechanism to move said plate in another direction to release said racks and to enable said racks to operate in clearing operations, a device controlled by a part of said plate-moving mechanism adapted to engage a part of said clearing mechanism to prevent operation thereof in each of several positions of said plate, means for engaging said device with a part of the clear-

- ing mechanism, and an actuating member controlled by the adding mechanism for releasing said device from the clearing mechanism to enable the clearing mechanism to operate. 5
3. In an adding machine, adding mechanism, racks for actuating said adding mechanism in adding and clearing operations, an element for engaging and preventing movement of said racks in clearing operations, mechanism for moving said element in one direction to selected positions to release selected numbers of said racks for adding operations, clearing mechanism operable to move said element in another direction to release said element from said racks to enable said racks to operate in clearing operations, a device controlled by a part of said moving mechanism for preventing operation of said clearing mechanism when any of said racks are out of their idle positions, automatic means for engaging said device with a part of said clearing mechanism, and an actuating member under control of the adding mechanism for releasing said device from the clearing mechanism. 10
4. In an adding machine, adding wheels, a support for said adding wheels, racks for operating said adding wheels in adding and clearing operations, an element for engaging and preventing operation of said racks in clearing operations, mechanism for moving said element in one direction to selected positions to release selected numbers of said racks for adding operations, clearing mechanism for coöoperating said racks and adding wheels in clearing operations, means operated by a part of the clearing mechanism to move said element in another direction out of position to engage said racks to enable said rack to operate said clearing mechanism, a device controlled by a part of said moving mechanism for engaging and preventing movement of said clearing mechanism when transferring is incomplete in the adding mechanism, and a member controlled by the adding mechanism to release said device as an incident to the completion of transferring in the adding mechanism to enable the clearing mechanism to operate after transferring has been completed. 15
5. In an adding machine, adding mechanism operable in adding and clearing operations, racks for operating said adding mechanism in adding and clearing operations, an element for holding said racks from movement in one direction, mechanism for moving said racks in one direction to selected positions to enable selected numbers of said racks to operate in adding operations, and clearing mechanism for moving said element in another direction to enable said racks to operate in clearing operations and for coöoperating said racks and adding mechanism, in combination with devices controlled by a part of said moving mechanism for engaging and preventing operation of said clearing mechanism when transferring in the adding mechanism is incomplete, and means actuated by the adding mechanism for releasing said devices as an incident to the completion of transferring in the adding mechanism to enable clearing mechanism to be operated thereafter. 70
6. In an adding machine, adding wheels, racks for operating the adding wheels, an element for holding said racks, mechanism for moving said element to selected positions in one direction to enable selected numbers of said racks to operate in adding operations, clearing mechanism for moving said element in another direction to enable said racks to operate in clearing operations for coöoperating with the adding wheels and racks in clearing operations, a part operated by said clearing mechanism for moving said element to position to enable said racks to operate in clearing operations, a device controlled by said moving mechanism for engaging said part to prevent movement thereof when transferring is incomplete in the adding wheels, a pivoted support for moving the adding wheels into and out of engagement with the racks, and a member actuated by said support for disengaging said device from said part to enable said part to be operated. 75
7. In an adding machine, adding wheels, a pivoted frame in which said adding wheels are mounted, racks with which said adding wheels are engaged by movement of said frame, an element for preventing movement of said racks, mechanism for moving said element to selected positions in one direction to enable selected numbers of said racks to operate in adding operations, automatic means for operating said frame to disengage said wheels from said racks when said racks move in one direction, clearing mechanism for holding said frame in position to retain said wheels and racks in engagement with each other when said racks move in the direction aforesaid, a device controlled by said moving mechanism for engaging and preventing operation of said clearing mechanism when transferring is incomplete in the adding wheels, a member actuated by said frame to disengage said device as an incident to the completion of transferring in the adding wheels, and means operated by the clearing mechanism for moving said element in another direction to enable said racks to operate in clearing operations. 80
8. In an adding machine, the combination with a series of adding wheels, a support for the adding wheels, a series of racks for operating said wheels in adding and clearing operations, elements for operating said racks and adding wheels in adding operations, an actuator for moving said elements and there- 85

- by said racks in a direction to operate said adding wheels in adding operations, and clearing mechanism for maintaining a co-operative relation between said wheels and 5 racks in clearing operations, of a device for preventing operation of the clearing mechanism, means for holding said device in position to prevent operation of said clearing mechanism after each adding operation of 10 said racks, a member for preventing movement of said racks in one direction, and means actuated by the support for the adding wheels, as an incident to an operation of said actuator when said member is holding 15 said racks, to move said device to position to enable the clearing mechanism to be operated.
9. In an adding machine, the combination with adding and clearing mechanisms, an 20 element for holding and preventing movement of parts of said adding mechanism, means for moving said element to selected positions in one direction to release parts of said adding mechanism for adding operations, and a member operated by the clearing mechanism for moving said element in another direction to release parts of said mechanisms for clearing operations, of a device controlled by said moving means for 25 engaging said member to prevent operation thereof when transferring is incomplete in the adding mechanism, and an actuating member operated by the adding mechanism for releasing said device as an incident to 30 the completion of transferring in the adding mechanism to enable said device to be actuated by the clearing mechanism to release said element.
10. In an adding machine, racks operable 40 in adding and clearing operations, a movable part for engaging and holding said racks, a support for moving said part in one direction to release said racks for adding operations, means for controlling the 45 movement of said support, a member operable to move said part in another direction to release said racks for clearing operations, a device controlled by said controlling means for engaging said member, a spring for 50 moving said device into engagement with said member, adding mechanism, a support in which said adding mechanism is mounted for co-operation with said racks, and a member actuated by said support for releasing 55 said device.
11. In an adding machine, clearing mechanism, a part connected with and movable by said clearing mechanism, a device movable into and out of engagement with said part, 60 a member for disengaging said device from said part, a support upholding said member, and means for moving said support and thereby said member to disengage the latter from said device and enable said device to 65 engage said part.
12. In an adding machine, the combination with differential mechanism, keys for setting up numbers in the differential mechanism, adding wheels, racks for operating the adding wheels in adding and transferring and clearing operations, and means for moving said adding wheels into and out of engagement with said racks, of clearing mechanism for effecting co-operation between said racks and said adding wheels in 70 clearing operations, a device under control of the differential mechanism independently of said racks for engaging a part of said clearing mechanism to prevent operation thereof in any position of the racks and after said 75 keys have returned to their idle positions, and a member operated by said adding wheel moving means to disengage said device from the clearing mechanism.
13. In an adding machine, number setting 80 mechanism adapted to have numbers set up therein and cleared therefrom, keys for setting up numbers in the number setting mechanism, adding wheels, racks for operating the adding wheels to add the numbers set 85 up in the number setting mechanism, clearing mechanism for causing said racks and adding wheels to co-operate in clearing operations, a device under control of the number setting mechanism independently of said 90 racks to engage and prevent operation of the clearing mechanism when any number is set up in the number setting mechanism before the racks have been operated in adding operations and also preventing operation of 95 the clearing mechanism after the racks have been operated in an adding operation in any position of said racks, and a member operated by the adding mechanism in a subsequent operation to engage said device and 100 move the same positively out of engagement with the clearing mechanism to enable the clearing mechanism to be operated.
14. In an adding machine, adding and clearing mechanisms, a device movable into 105 engagement with the clearing mechanism to prevent operation thereof, a member holding said device out of engagement with the clearing mechanism, an actuator for moving said member to release said device, a spring 110 for engaging said device with said clearing mechanism when said device is released, key-controlled means for restoring said actuator to its normal position, and means for operating said member to disengage said device 115 from the clearing mechanism.
15. In an adding machine, the combination of racks adapted to be operated in adding and clearing operations, and an element holding said racks, of a movable part 120 for releasing said element from said racks, a device for engaging and holding said part, a member holding said device out of engagement with said part, an actuator for disengaging said member from said device 125 130

- to enable said device to engage said part, a shaft, a cam on said shaft engaging and preventing said actuator from releasing said member from said device, means for turning 5 said shaft in one direction to release said cam from said actuator, and means for turning said shaft in the opposite direction to cause said cam to restore said actuator to its idle position.
- 10 16. In an adding machine, the combination of number-setting mechanism, adding wheels, racks for coöperating with said number-setting mechanism to introduce into the adding wheels the numbers represented by 15 the number-setting mechanism, a part engaging and holding said racks and movable out of engagement therewith by the number-setting mechanism, clearing mechanism for coöperating said racks and adding wheels in 20 clearing operations, a device adapted to engage with the clearing mechanism to prevent operation thereof, a member holding said device out of engagement with the clearing mechanism, an actuator for disengaging 25 said member from said device, means controlled by the number-setting mechanism for preventing operation of said actuator and enabling said actuator to operate to disengage said member from said device as an 30 incident to the setting of a number, manual means for restoring the number-setting mechanism and said actuator to idle position, and means for operating said member to disengage said device from the clearing 35 mechanism.
17. In an adding machine, clearing mechanism, a device for engaging and preventing operation of said clearing mechanism, a member for holding said device out 40 of engagement with said clearing mechanism, an actuator for disengaging said member from said device, means for operating said device into engagement with the clearing mechanism when said member is released, means for restoring said actuator to idle position, and additional means for 45 operating said member to disengage said device from the clearing mechanism.
18. In an adding machine, clearing 50 mechanism, a pivoted frame, a device for engaging and preventing operation of said clearing mechanism, a member connected with said pivoted frame for holding said device disengaged from the clearing mechanism, an actuator for disengaging said member from said device, means for restoring 55 said actuator to idle position, and additional means for operating said pivoted frame and thereby said member to disengage said device from the clearing mechanism.
19. In an adding machine, clearing 60 mechanism, adding mechanism controlled by said clearing mechanism, a pivoted frame, a device for engaging and preventing operation of said clearing mechanism, a member 65
- connected with said pivoted frame for holding said device disengaged from said clearing mechanism, an actuator for disengaging said member from said device, mechanism holding said actuator in position in 70 which said member will remain in engagement with said device, means for operating said mechanism to release said actuator, means for operating said actuator to release said member from said device, manual means 75 for operating said mechanism to restore said actuator to idle position, and additional means for operating said frame and thereby said member to disengage said device from the clearing mechanism. 80
20. In an adding machine, adding and clearing mechanisms, a device for engaging and preventing operation of the clearing mechanism, a member for holding said device disengaged from the clearing mechanism, an actuator for disengaging said member from said device, a shaft, a part controlled by said shaft for holding said actuator in position in which said member may hold said device disengaged from the 90 clearing mechanism, means for operating said shaft to enable said actuator to disengage said member from said device, manual means for operating said shaft to restore the actuator to idle position, and additional 95 means for operating said member to disengage said device from the clearing mechanism. 100
21. In an adding machine, clearing mechanism, a device for engaging and preventing operation of said clearing mechanism, a member for holding said device disengaged from the clearing mechanism, an actuator for releasing said member from said device, a shaft controlling operation of said actuator, means for operating said shaft in one direction to enable said actuator to operate, manual means for operating said shaft in the opposite direction to restore said actuator to idle position, and independently operable means for operating said member to disengage said device from the clearing mechanism. 105
22. In an adding machine, a rock shaft, a carriage connected with said rock shaft, an actuator for turning said rock shaft in one direction, a link connected with said rock shaft, an additional rock shaft, manual means for rocking the additional rock shaft in one direction and thereby rocking the first-mentioned rock shaft to restore the carriage to the starting point, and a spring for restoring the additional rock shaft to idle position. 110
23. In an adding machine, clearing mechanism, a device for engaging and preventing operation of the clearing mechanism, a member for holding said device out of engagement with the clearing mechanism, an actuator for disengaging said member from said 115
- 120
- 125
- 130

device, a rock shaft preventing operation of said actuator, means for turning said shaft in one direction to enable said actuator to operate, an additional rock shaft, manual 5 means for rocking said additional rock shaft in one direction, connections from said additional rock shaft for turning the first-mentioned rock shaft to its starting point and to restore said actuator to idle position, a third 10 rock shaft, and mechanism controlled by the third rock shaft for operating said member to disengage said device from the clearing mechanism.

24. In an adding machine, clearing mechanism, a device for engaging and preventing 15 operation of said clearing mechanism, a member holding said device disengaged from the clearing mechanism, an actuator for releasing said member from said device, 20 a rock shaft holding said actuator in position in which said member is in engagement with said device, means for turning said rock shaft in one direction to enable said actuator to operate, manual means for 25 turning said rock shaft in the opposite direction to restore said actuator to idle position, a rock shaft operable independently of said manual means, and mechanism controlled by said second-mentioned rock shaft 30 for operating said member to disengage said device from the clearing mechanism.

25. In an adding machine, clearing mechanism, a device for engaging and preventing 35 operation of the clearing mechanism, a member holding said device out of engagement with the clearing mechanism, an actuator for disengaging said member from said device, a shaft preventing operation of said actuator, means for turning said shaft in 40 one direction to position to enable said actuator to operate, optionally operable means for turning said shaft in opposite direction to restore said actuator to idle position, a pivoted frame, and mechanism for operating 45 said pivoted frame and thereby said member to disengage said device from the clearing mechanism.

26. In an adding machine, the combination 50 with printing type, a hammer for coöperating with said type to print, and an actuator for said hammer, of a coupling movable to and from position to couple said actuator and said hammer, a lever for moving said coupling to position to couple said 55 actuator and hammer, an additional lever for operating the one mentioned, and means for operating said additional lever.

27. In an adding machine, printing type, a hammer for coöperating with said type to 60 effect printing, an actuator for said hammer, a coupling movable to and from position to connect said actuator and hammer, a lever for moving said coupling to position to connect said actuator and hammer, an additional lever for operating the one men-

tioned, an actuator for said additional lever, and means for operating said actuator.

28. In an adding machine, a type-carrier movable to and from selected recording positions, type carried by said type-carrier, a hammer for coöperating with said type to effect printing, an actuator for said hammer, a coupling for connecting and disconnecting said actuator and hammer, a lever for moving said coupling to position to connect said actuator and hammer, means whereby said type-carrier when moved to certain recording positions will operate said lever, and means for operating said lever independently of said type-carrier. 75

29. In an adding machine, type-carriers, adding mechanism operable in adding and clearing operations, hammers for coöperating with said type-carriers to print, actuators for said hammers, couplings for connecting 80 and disconnecting said actuators and hammers, levers for moving said couplings to position to connect said actuators and hammers, means for operating said levers by said type-carriers, an additional lever for 85 operating one of said levers, and means for operating said additional lever.

30. In an adding machine, the combination with type-carriers, mechanism for operating said type-carriers, and adding mechanism controlled by said type-carriers, of hammers for coöperating with said type-carriers to effect printing, actuators for 90 said hammers, couplings movable to and from position to connect said actuators and hammers, levers for moving said couplings to position to connect said actuators and hammers, means for operating said levers by said type-carriers, and means under control of said adding mechanism for operating one of said levers to move one of said couplings to position to connect one of said actuators with the corresponding hammer. 95

31. In an adding machine, the combination with adding and clearing mechanisms, 100 of a device, for printing a character to indicate a clear condition of the adding mechanism, comprising a type-carrier, a type carried by said type-carrier, a hammer for coöperating with said type to print, an 105 actuator for said hammer, a coupling movable to and from position to connect said actuator and hammer, means for holding said coupling in position in which said actuator and hammer are disconnected, a lever for 110 moving said coupling to position to connect said hammer and actuator, and means operated by the adding mechanism for operating said lever.

32. In an adding machine, the combination with type carriers movable to select 115 printing positions, hammers for coöperating with the type on said type-carriers, actuators for said hammers, couplings movable to and from position to connect said ham- 120

125

130

mers and actuators, adding mechanism arranged to coöperate with said type-carriers in adding and clearing operations, mechanism operated by said type-carriers for moving said couplings to position to connect said actuators and hammers as an incident to the operation of said type-carriers and adding mechanism in adding and clearing operations, and means controlled by said

5 adding mechanism for moving one of said couplings to position to connect one of said actuators with the corresponding hammer.

10

33. In an adding machine, the combination of a type-carrier movable to selected printing positions, a hammer for coöperating with the type on said type-carrier in any of its printing positions, an actuator for said hammer, a coupling for connecting and disconnecting said hammer and actuator, a

15 lever for positioning said coupling to connect said actuator and hammer, means whereby said type-carrier will operate said lever when said type-carrier is moved to all except one of its printing positions, adding mechanism, and connections under control of said adding mechanism for operating said lever to move said coupling to position to connect said hammer and actuator when said type-carrier is moved to that

20 printing position in which said type-carrier will not operate said lever.

25

34. In an adding machine, the combination with adding and clearing mechanisms, a type, and means for supporting said type in printing position when the adding mechanism is clear, a hammer for driving the type to print, a normally deënergized actuator for said hammer, a coupling movable to and from position to connect said actuator and hammer, means controlled by said adding mechanism for moving said coupling to position to connect said actuator and hammer, and means for energizing said actuator and operating the same to drive the hammer to

30 print.

35

35. In an adding machine, a type, adding mechanism, and clearing mechanism for coöperating said type and adding mechanism, a hammer for driving the type to print, a normally deënergized actuator for said hammer, a coupling movable to and from position to connect said actuator and hammer, mechanism controlled by the adding mechanism for moving said coupling to position to connect said actuator and hammer, means for energizing said actuator, a device for preventing operation of said hammer while said actuator is being energized, and means for releasing said device after said actuator

40 has been energized.

45

36. In an adding machine, adding mechanism, a printing type for printing a character to indicate a clear condition of the adding mechanism, and clearing mechanism for

50 clearing the adding mechanism, in combina-

tion with a hammer for driving said type to print, a normally deënergized actuator for said hammer, a coupling for connecting and disconnecting said hammer and actuator, mechanism controlled by the adding mechanism for supporting said coupling in position to connect said actuator and hammer, mechanism for energizing said actuator and operating the same to drive the hammer to print, and a device for restoring said hammer to idle position after operation by said actuator.

55

37. In an adding machine, adding mechanism, clearing mechanism for clearing the adding mechanism, a type for printing a character to indicate a clear condition of the adding mechanism, a hammer for coöperating with said type to effect printing, a normally deënergized actuator for said hammer, mechanism controlled by the adding mechanism for enabling said actuator and hammer to coöperate, means for energizing said actuator and operating the same to operate said hammer, a device for restoring said actuator to idle position, and an additional device for restoring said hammer to idle position.

60

38. In an adding machine, adding mechanism, type-carriers, means for coöperating said type-carriers and adding mechanism, hammers for driving the type on said type-carriers to print, normally deënergized actuators for said hammers, couplings for connecting and disconnecting said actuators and hammers, levers operable automatically to move said couplings to position to connect said actuators and hammers as an incident to the coöperation of said adding mechanism and type-carriers, means for energizing said actuators, a device for preventing operation of said hammers while said actuators are being energized, means for operating said device to restore said hammers to idle position, an additional device for restoring said actuators to idle position, means normally holding certain of said couplings in position in which the hammers and actuators are disconnected, and means controlled by the adding mechanism normally holding one of said couplings in position to connect one of said actuators and hammers.

65

39. In an adding machine, a series of type carriers, a series of hammers for driving the type on said type carriers to print, a series of actuators for said hammers respectively, couplings for connecting and disconnecting said actuators and hammers, means normally holding certain of said couplings in position in which the corresponding hammers and actuators are disconnected, and means normally holding one of said couplings in position in which the corresponding actuator and hammer are connected.

70

40. In an adding machine, a series of type carriers a series of hammers for driving the

75

type on said type carriers to print, normally deenergized actuators for said hammers, couplings for connecting and disconnecting said actuators and hammers, means normally holding certain of said couplings in position in which the corresponding hammers and actuators are disconnected, means for moving said couplings to position to connect said actuators and hammers, means normally holding one of said couplings in position to connect the corresponding actuator and hammer, and mechanism for energizing said actuators and operating them to actuate the hammers.

41. In an adding machine, a series of type-carriers, a series of hammers for driving the type to print, normally deenergized actuators for said hammers, couplings for connecting and disconnecting said actuators and hammers, means normally holding certain of said couplings in position in which the corresponding actuator and hammer are connected, means controlled by the type-carriers for moving the remaining couplings to position to connect the type-carriers and hammers, and mechanism for energizing and operating the actuators which are connected with the corresponding hammers.

42. In an adding machine, a series of type-carriers, a series of hammers for driving the type to print, normally deenergized actuators for said hammers, couplings for connecting and disconnecting said actuators and hammers, means normally holding certain of said couplings in position in which the corresponding actuators and hammers are disconnected, means for holding one of said couplings in position in which the corresponding actuator and hammer are connected, means controlled by the type-carriers for moving the remaining couplings to position to connect the type-carriers and hammers, and mechanism for energizing and operating the actuators which are connected with the corresponding hammers while the actuators which are not connected with their hammers remain deenergized.

43. In an adding machine, a type-carrier, a hammer for driving the type on said type carrier to print, a normally deenergized actuator therefor, a coupling for connecting and disconnecting said actuator and hammer, a lever for supporting said coupling in position to connect said actuator and hammer, a device for holding said lever in position to support said coupling in position to connect said actuator and hammer, means for energizing said actuator, a device holding said hammer while said actuator is being energized, means for releasing said device to enable said actuator to operate said hammer, and means for operating said

device to restore said hammer to idle position.

44. In an adding machine, a type-carrier, a hammer for driving the type on said type-carrier to print, a normally deenergized actuator therefor, a coupling for connecting and disconnecting said actuator and hammer, means normally holding said coupling in position to connect said actuator and hammer, means for moving said coupling to position to disconnect said actuator and hammer, means for energizing said actuator when said actuator is connected with said hammer by said coupling, a device for preventing operation of said hammer when said actuator is being energized, means for releasing said device to enable said hammer to be operated, and means for restoring said actuator to idle position.

45. In an adding machine, a type-carrier, a hammer for driving the type on said type-carrier to print, a normally deenergized actuator therefor, a coupling movable to and from position to connect said actuator and hammer, a movable part, means controlled by said movable part when in one position for supporting said coupling in position to connect said actuator and hammer, mechanism for retaining said movable part in the position mentioned, and mechanism for energizing and operating said actuator and thereby said hammer.

46. In an adding machine, a type-carrier, a hammer for driving the type on said type-carrier to print, a normally deenergized actuator therefor, adding mechanism movable to and from operative position, a coupling for connecting and disconnecting said actuator and hammer, and mechanism controlled by said adding mechanism when in operative position for supporting said coupling in position to connect said actuator and hammer.

47. In an adding machine, adding mechanism, a type, a hammer for driving said type to print a character to indicate a clear condition of the adding mechanism, a normally deenergized actuator for said hammer, means for preventing said actuator from being energized when said adding mechanism is out of operative position, mechanism for supporting said adding mechanism in operative position and for energizing said actuator, and a device controlling the operation of said hammer by said actuator.

48. In an adding machine, adding mechanism movable to and from operative position, a type, a hammer for driving said type to print, an actuator for said hammer, a coupling for connecting and disconnecting said actuator and hammer, a lever for supporting said coupling in position to connect said actuator and hammer, means controlled by said adding mechanism when in operative position for holding said lever in position.

tion to support said coupling as required to connect said actuator and hammer, and means for moving said coupling to position to disconnect said actuator and hammer 5 when said adding mechanism is out of operative position.

49. In an adding machine, adding mechanism movable to and from operative position, a device preventing displacement 10 of said adding mechanism when out of operative position, a type, a hammer for driving said type to print, a normally deenergized actuator for said hammer, a coupling for connecting and disconnecting said actuator 15 and hammer, mechanism controlled by said adding mechanism when in operative position for supporting said coupling in position to connect said actuator and hammer, a device for moving said coupling to position 20 to disconnect said actuator and hammer when said adding mechanism is out of operative position, and mechanism for energizing and operating said actuator.

50. In an adding machine, adding 25 mechanism movable to and from operative position, a device for preventing displacement of said adding mechanism when out of operative position, a type, a hammer for driving said type to print, a normally deenergized actuator for said hammer, a coupling controlled by said adding mechanism for connecting said actuator and hammer, means

for energizing said actuator, a device preventing operation of said hammer while said actuator is being energized, means for operating said device to release said hammer, means for operating said device to restore said hammer to idle position, and a device for restoring said actuator to idle position. 40

51. In an adding machine, type, a type-driving hammer for driving said type to print, and a normally deenergized actuator therefor, in combination with a coupling 45 movable to and from position to connect said actuator and hammer, a spring for moving said coupling to disconnect said actuator and hammer, a lever for moving said coupling to position to connect said actuator and hammer, adding mechanism, 50 means for supporting said adding mechanism in different positions, means controlled by said adding mechanism in one position thereof for holding said lever in position to cause said coupling to connect said actuator and hammer, and means for operating said actuator. 55

In witness whereof, I have signed this specification in the presence of two subscribing witnesses.

HARRY LANDSIEDEL.
